Related U.S. Application Data

(62) Division of application No. 29/616,827, filed on Sep. 8, 2017, now Pat. No. Des. 883,391.

(57) **CLAIM**
I claim the ornamental design for a bank of combined gaming machines and displays, as shown and described.

(51) **LOC (14) Cl.** **21-03**

DESCRIPTION

(52) **U.S. Cl.**

FIG. 1 is a perspective view of a bank of combined gaming machines and displays in accordance with the new design. FIG. 2 is a right side view of the bank of combined gaming machines and displays shown in FIG. 1. FIG. 3 is a left side view of the bank of combined gaming machines and displays shown in FIG. 1. FIG. 4 is a top view of the bank of combined gaming machines and displays shown in FIG. 1. FIG. 5 is a front view of the bank of combined gaming machines and displays shown in FIG. 1; and, FIG. 6 is a back view of the bank of combined gaming machines and displays shown in FIG. 1.

USPC **D21/369**

The broken line showing portions of the bank of combined gaming machines and displays depicts environment and forms no part of the claim.
